SANDBLAST TOOL

Charles E. Archer, Birmingham, Mich., assignor
to Ex-Cell-O Corporation, Detroit, Mich., a
corporation of Michigan

Application October 30, 1943, Serial No. 508,291

6 Claims. (Cl. 51—11)

This invention relates to a sand blast tool and more particularly to a sand blast tool adapted to be received in a bore having laterally extending passages and to provide a lateral discharge nozzle for directing the blast into the laterally extending passages of the bore.

Heretofore, it has been the general practice in sand blasting comparatively small, cored passages, and particularly tortuous passages, to divert the blast of sand by a correspondingly shaped passage in the sand blast tool causing the sand to impinge on the wall of the sand blast conduit. This causes a rapid wearing away of the tool conduit and repeated replacement.

It is, therefore, an object of this invention to provide a sand blast nozzle having a fluid pressure conduit which delivers the pressure through a tortuous passage before the sand is mixed with the fluid pressure so that there is no diversion of sand under pressure.

Another object of the invention is to provide a header member having a fluid pressure chamber and a sand chamber with separate passages extending longitudinally through a member adapted to be received in a cored opening and having a laterally extending discharge passage for the fluid pressure communicating with the longitudinally extending sand passage.

A further object of the invention is to provide a header having a fluid pressure chamber and a separated sand chamber and a rotatable, tubular member provided with separate passages communicating respectively with the fluid pressure chamber and the sand chamber.

Other objects and advantages of the invention will be more fully understood from the following description taken in connection with the accompanying drawing in which:

Fig. 1 is a longitudinal sectional view through my improved sand blast tool showing the same received in a cored passage having laterally extending passages;

Fig. 2 is a plan view of the tool shown in Fig. 1; and

Fig. 3 is a sectional view taken on line 3—3 of Fig. 1.

Referring to the drawing, the tool comprises a header 10 having a central fluid pressure chamber 12 and a sand chamber 14. A pipe 16 is fitted into a wall 18 which separates the two chambers 12 and 14 forming a conduit from the fluid pressure chamber 12 through the sand chamber 14. Both the pipe 16 and sand chamber 14 are coaxial. The discharge end of the sand chamber 14

is shown as an annular passage and receives one end of a tubular member 20.

The one end of the tubular member 20 is provided with an annular flange 22 which is received against the outer surface of the header 10 and is held in rotatable position thereon by a collar 24 having screw thread engagement with the end of the header 10. The tubular member 20 is projected longitudinally beyond the end of the header 10 and is adapted to be inserted in a longitudinally extending bore 26 of a workpiece 28, such as a cored casting having transversely extending passages 30.

When it is desired to remove core sand, scale or the like from passages extending at an angle to another passage through which the sand blast tool is inserted, it is necessary to conduct the blast, first in a direction corresponding to the direction of the first passage and then divert the direction of blast so that it is directed into the lateral passages. Heretofore, this has been done by diverting the stream of mixed fluid pressure and sand in a tortuous path. This causes an abrasive action on the diverting wall with the result that the parts of the passages are quickly worn and must be replaced.

By my improved construction I maintain a separation of fluid pressure and sand until the fluid pressure has been diverted into the required direction after which the sand is admitted to the fluid pressure stream. Thus the sand does not impinge on the walls of the conducting conduits.

The end of the tubular member 20 adjacent the header 10 is provided with an annular sand passage 32 surrounding the pipe 16 which forms a fluid pressure passage 34. A member 36 having a cylindrical outer end portion substantially the diameter of the passage 32, has one side thereof cut away on a diagonal line forming a flat face 38 for directing the sand in the passage to one side at the outer end of the tubular member 20. A central opening 40 is formed in the member 36 to receive the outer end of the fluid pressure pipe 16. A passage 42 is formed in the member 36 for conducting the sand therethrough.

At the outer end of the tubular member 20 is a nozzle fitting 44 which has screw-thread engagement with the tubular member 20. This nozzle 44 is of a dimension substantially equal to the diameter of the tubular member 20 and both are of minimum size so that the tool may be easily inserted into openings of comparatively small dimension.

The nozzle 44 is provided with two axially extending passages 46 and 48 which register with

the passages 34 and 42 respectively. A transverse passage 50 opening through one side of the nozzle intersects the passages 46 and 48. A replaceable wear member 52 is fitted in the open end of the passage 50. By this arrangement of parts the sand is fed by gravity into the passage 50 where it is picked up by the diverted fluid pressure without being caused to impinge the walls of the passages in the sand blast tool.

A collar 52 is received on the outer periphery of the tubular member 20 and is adjustably held in any desired location by screws 54 which also serve as handles to rotate the tubular member 20 within the bore 26 so that the discharge opening 50 of the nozzle 44 may be rotated to apply a sand blast to all portions of passages 30. The collar 52 also serves as a stop to limit the depth at which the nozzle is inserted in the bore 26.

The compact arrangement of parts makes possible a sand blast tool of minimum dimension so that it may be inserted in small passages and by mixing the sand with the fluid pressure after the fluid pressure has been diverted from its path longitudinally of the tool, wearing of the tool parts, heretofore caused by impingement of sand at high velocity against a diverting member, has been eliminated.

It will be understood that various changes including the size, shape and arrangement of parts may be made without departing from the spirit of my invention and it is my intention to cover, by the appended claims, such changes as may be reasonably included within the scope thereof.

I claim as my invention:

1. A sand blast tool comprising a header having a fluid pressure receiving chamber and a sand receiving chamber, a fluid pressure delivery pipe communicating with said pressure chamber and projecting beyond the end of said header, a tubular member connected to said header surrounding said pipe and communicating with said sand chamber to form a sand passage between said tubular member and said pipe, and a nozzle having a diameter substantially equal to the diameter of said tubular member detachably received at the outer end of said tubular member and having a side discharge opening directed substantially at right angles to the direction of said pipe and tubular member, said side discharge opening communicating with a longitudinally extending passage in said nozzle registering with the open end of said delivery pipe, and communicating with a longitudinally extending passage registering with the open end of the passage between said tubular member and said pipe and located between the discharge opening and said fluid pressure delivery pipe.

2. A sand blast tool comprising a header having a fluid pressure receiving chamber and a sand receiving chamber, a fluid pressure delivery pipe communicating with said pressure chamber and projecting beyond the end of said header, a tubular member connected to said header surrounding said pipe and communicating with said sand chamber to form a sand passage between said tubular member and said pipe, means accessible to the operator for rotating said tubular member relative to said header when said nozzle is within a workpiece, and a nozzle having a diameter substantially equal to the diameter of said tubular member detachably received at the outer end of said tubular member and having a side discharge opening directed substantially at right angles to the direction of said pipe and tubular member, said side discharge opening com-

municating with a longitudinally extending passage in said nozzle registering with the open end of said delivery pipe and communicating with a longitudinally extending passage between said last mentioned longitudinally extending passage and said discharge opening, and registering with the open end of the passage between said tubular member and said pipe.

3. A sand blast tool comprising a header having a fluid pressure receiving chamber and a sand receiving chamber, a fluid pressure delivery pipe communicating with said pressure chamber and projecting beyond the end of said header, a tubular member connected to said header surrounding said pipe and communicating with said sand chamber to form a sand passage between said tubular member and said pipe, said tubular member being rotatable relative to said header, a nozzle having a diameter substantially equal to the diameter of said tubular member detachably received at the outer end of said tubular member and having a side discharge opening directed substantially at right angles to the direction of said pipe and tubular member, said discharge opening communicating with a longitudinally extending passage in said nozzle registering with the open end of said delivery pipe and connecting with a longitudinally extending passage registering with the open end of the passage between said tubular member and said pipe, and a longitudinally adjustable sleeve on the outer periphery of said tubular member for engagement with the work to variably position the nozzle within the work.

4. A sand blast tool comprising a header having a fluid pressure receiving chamber and a sand receiving chamber, a delivery pipe communicating with said pressure chamber and projecting beyond the end of said header, a tubular member connected to said header surrounding said pipe and communicating with said sand chamber to form a sand passage between said tubular member and said pipe, a member within said tubular member having one side cut away forming a flat diagonal surface for directing sand around said pipe to one side adjacent the outer end of said tubular member and having spaced openings therethrough, one to communicate with the opening in said pipe and forming a support for said pipe and the other forming a communication with the sand passage at one side of said tubular member, and a nozzle having an outside dimension substantially equal to the diameter of said tubular member and having a side discharge passage intersecting the spaced openings in said member within said tubular member.

5. A sand blast tool comprising a header having a fluid pressure receiving chamber and a sand receiving chamber, separated coaxial passages extending substantially parallel from said header and communicating respectively with said pressure chamber and said sand chamber, and a nozzle having a fluid pressure passage and a sand passage communicating respectively with said parallel passages and forming straight line continuations thereof, said fluid pressure passage having a discharge opening extending in a direction at an angle to said parallel passages and intersecting said sand passage at right angles thereto adjacent the discharge opening.

6. A sand blast tool comprising a header having a fluid pressure receiving chamber and a sand receiving chamber, a fluid pressure delivery pipe communicating with said pressure chamber and projecting beyond the end of said header, a

tubular member connected to said header surrounding said pipe and communicating with said sand receiving chamber to form a sand passage between said tubular member and said pipe, and a nozzle having a fluid passage open to said pipe and a lateral discharge passage extending transversely of said pipe and intersecting said fluid

passage, and having a longitudinal passage communicating with said sand passage and intersecting said lateral discharge passage at a point between said fluid passage and the discharge end 5 of said lateral discharge passage.

CHARLES E. ARCHER.
